CHATTER SWITCH

Harry H. Hall, 1523 28th St. SE., Washington, D.C., and Whitney A. Brown, 15369 Tuller, Detroit, Mich.

Filed June 8, 1945, Ser. No. 598,351

2 Claims. (Cl. 200—61.01)

(Granted under Title 35, U.S. Code (1952), sec. 266)

This invention relates generally to chatter switches and more particularly to a chatter switch which is adapted to be set in operation in response to acoustic energy received thereby through an elastic medium, the principal object being to provide a new and improved chatter switch having a novel construction, combination and arrangement of the parts thereof adapted to receive, without damage thereto or operational impairment thereof, abnormally large amounts of energy such as may be received when the switch is employed in mines, depth charges or the like.

Another object is the provision of a new and improved chatter switch responsive to sound signals of predetermined frequency.

Another object is the provision of a new and improved chatter switch wherein means are provided for adjusting the sensitivity of the switch.

Still another object is to provide a new and improved chatter switch for use in marine mines and wherein means are provided for substantially equalizing the static pressure head on the element in communication with the surrounding water.

In accordance with the preferred embodiment of the present invention, a pair of normally closed, whisker type contacts are employed, one of the contacts being carried by a balance wheel mounted on a shaft and rotatable therewith. Also mounted on the shaft is a resilient spring member which is adapted to exert tension on the shaft and balance wheel variably in accordance with the setting of suitable adjusting means provided therefor. The other contact is secured to a post member which in turn is clamped to a flexible diaphragm. The normally closed contacts are adapted to be disengaged at intervals as the diaphragm is set in vibration by sound signals of sufficient strength to overcome the tension exerted on the balance wheel, such vibration being transmitted through the post member to the contact mounted thereon.

The invention, as well as additional objects and advantages thereof, will be best understood by referring to the following description taken in connection with the accompanying drawings wherein like reference characters refer to like parts throughout the several views and in which:

Fig. 1 is a sectional view of the device of the present invention;

Fig. 2 is a fragmentary sectional view taken substantially along the line 2—2 of Fig. 1;

Fig. 3 is a sectional view taken substantially along the line 3—3 of Fig. 2;

Fig. 4 is a view in section taken substantially along the line 4—4 of Fig. 3;

Fig. 5 is a fragmentary view in section taken substantially along the line 5—5 of Fig. 3; and,

Fig. 6 is a fragmentary sectional view taken substantially along the line 6—6 of Fig. 3.

Referring now to the drawings for a more detailed description of the invention and particularly to Figs. 1 through 6 inclusive, there is shown thereon a chatter

2

switch or sound responsive device generally designated by the numeral 10 and comprising a support 11 secured to a circular base 12 as by a plurality of screws 13. Also secured to the base 12 is a casing 14 for the switch, 5 which casing is provided with a circular flanged portion 15 having a plurality of holes therein adapted to receive the screws 16. A thin flexible diaphragm 17, preferably circular in shape and of a material suitable for the purpose such, for example, as beryllium copper or sheet metal, is mounted between the base 12 and the support 11 with suitable gasket means 18 arranged between the base and diaphragm. The base 12 is provided with a recessed aperture 19 which allows sound signals or pressure impulses to impinge against the outer surface 15 of the diaphragm 17.

The diaphragm 17 and support 11 are provided with coincident apertures within which is disposed a mass or post 21 securely clamped to the diaphragm by means of a packing nut 22 screwed to a threaded extremity of 20 the post 21, thereby causing the post to vibrate as the diaphragm vibrates. A suitable gasket 23 is mounted between the packing nut and diaphragm to insure a watertight relation therebetween. It should be noted that the support 11 limits the vibrational amplitude of the 25 diaphragm.

Secured to the support 11 by means of the screws 24 are two mounting strips 25 and 26, each being electrically insulated from the other and from the screws 24 by a strip of suitable insulating material 27 such, for example, 30 as rubber, Bakelite or the like, the strip 26 also being insulated from the support by an additional strip of similar insulating material. The mounting strip 26 has two upright portions 28 and 29, the portion 28 having a threaded hole therein adapted to receive the adjustable 35 screw bearing 31, the portion 29 also being provided with a threaded hole therein adapted to receive the adjustable screw bearing 32. A lock nut 33 is disposed around the screw bearing 32 for maintaining the bearing 32 in an adjusted position with respect to the upright 40 portion 29.

Disposed about the screw bearing 31 is an internally bored, circular member 34 and releasably clamped between the member 34 and support 28 by the screws 35 45 is a ring member 36 having a relatively large inside diameter with respect to that of the member 34. Extending from the member 36 is an arm 37 which may be rotated to any desired setting by loosening the screws 35 and rotating the ring member 36. Secured to the arm 37 is a resilient spring 38 known in the trade as a hair spring, the other end of which is in engagement with a shaft 39. The shaft 39 is tapered at the ends thereof and is mounted for rotation in the bearings 31 and 32. An inertia member or light weight balance wheel 41 is secured to the shaft 39 and rotatable therewith. A long, 55 resilient or whisker type electrical contact 42 is mounted on the balance wheel and is yieldably held by means of the hair spring 38 in continuous engagement with another long, resilient or whisker type contact 43 when the switch is in a state of rest. The contact 43 is affixed to the post 21 and insulated therefrom by means of 60 suitable insulating material 44, the contact 43 also being arranged at right angles to the contact 42. It will be noted that the pressure between the contacts 42 and 43 is maintained at a predetermined value by the tension of the hair spring 38 in accordance with the setting of the ring member 36.

The conductor 45 is soldered to contact 43, thereby maintaining the conductor in electrical connection with contact 43. Similarly, conductor 46 is soldered to the 65 mounting strip 25, thereby maintaining conductor 46 in electrical connection with contact 42.

A suitable cup-shaped cover 47 is secured to the sup-

port 11 by a plurality of screws 48, the cover having arranged therein a partition 49 provided with a flanged portion 51 wherein a hole is drilled which is adapted to receive the post 21. In the bottom of the cover are a plurality of holes through which the conductors 45 and 46 are passed with encasing means 52 being provided for each conductor. A suitable gasket 53 is mounted between the cover 47 and support 11, thereby insuring a watertight connection therebetween.

The device is also provided with a rubber sack 54 arranged within the casing 14, the sack being securely clamped between the base 12 and the flanged portion 15. Cut into the flanged portion 15 is an opening or port 55 which allows water to pass into the space between the casing 14 and sack 54 when the chatter switch is submerged, thereby deflating the sack and causing the air enclosed thereby to be compressed. A hole 56 in the cover 47 also allows the air within the cover to be compressed and by reason of a plurality of holes 57 cut in the support 11, the resulting air pressure is applied to the inner surface of the diaphragm 17 to balance the water pressure on the outer surface thereof.

A housing 58 is secured to the casing 14, the housing having holes cut in the top and bottom surfaces thereof through which the cable 59 containing conductors 45 and 46 is passed. A plurality of holes are also cut in the casing 14 to allow passage therethrough of the conductors 45 and 46, with suitable encasing means 61 being provided at each hole in the casing 14 and housing 58 to prevent leakage of water into the device. It will be noted that the sack 54 is securely clamped between the housing 58 and casing 14.

A brief description of the operation of the present invention in connection with submarine mines will now be given. Let it be assumed that the chatter switch 10 has been mounted on a mine casing 62 by means of the screws 16 and has been submerged in a body of water. Let it further be assumed that the contacts 42 and 43 comprise a control circuit (not shown) for the mine carrying the switch and that the sensitivity of the contacts has been manually adjusted in order that weak sound signals striking the diaphragm 17 will not cause the contacts to be disengaged. Let it be assumed still further that the diaphragm 17 has been tuned to a frequency resident in the range of sound frequencies transmitted by a surface vessel moving within the vicinity of the switch.

When the switch 10 is submerged, the diaphragm 17 is subject to the pressure of the surrounding water and to compensate for this, the water flowing in the port 55 causes the rubber sack 54 to collapse partially, thereby substantially equalizing the pressures acting upon the inner and outer surfaces of the diaphragm, as heretofore described.

When a sound signal or pressure impulse of sufficient strength to overcome the pressure maintained between the contacts 42 and 43 by the hair spring 38 and of a frequency substantially corresponding to the inherent resonance frequency of the diaphragm 17 is transmitted through the surrounding water and impinges against the outer surface of the diaphragm, the diaphragm is set in vibration. When this occurs, the mass or post 21 also vibrates by reason of the packing nut 22 which secures the post to the diaphragm. As the post vibrates, the whisker type contact 43 carried thereby is caused to strike the resilient contact 42 mounted on the balance wheel or inertia member 39 and cause the contact 42 and balance wheel to vibrate thereby causing the control circuit comprising contacts 42 and 43 to be interrupted at intervals.

In the event a countermining explosion occurs within the vicinity of the switch and abnormally large amounts of acoustic energy resulting therefrom strike the diaphragm 17, the resilience of the whisker type contacts and the relatively light weight of the balance wheel provided

in the switch of the present invention preclude the possibility of damage or operational impairment to these elements. Moreover, if the contacts are set in vibration vigorously, the arrangement of the contacts at right angles to each other precludes the possibility of a failure thereof to close intermittently. It should be pointed out that the diaphragm 17 and mass 21, and the contact 43 and the inherent mass thereof comprise a two mass vibratory system whereby the vibrational amplitude of the contact 43 is greater than that of the diaphragm 17.

From the foregoing, it should now be apparent that a device has been provided which is well adapted to fulfill the aforesaid objects of the invention. While the invention has been described with particular reference to an embodiment thereof which gives satisfactory results, it will readily be apparent to those skilled in the art to which the invention pertains, after understanding the invention herein described, that further embodiments, modifications and changes may be made without departing from the spirit and scope thereof, as defined by the claims appended hereto.

The invention herein described and claimed may be manufactured and used by or for the Government of the United States of America without payment of any royalties thereon or therefor.

What is claimed as new and desired to be secured by Letters Patent of the United States is:

1. A device of the character disclosed adapted to be immersed in a body of water and comprising a casing having two openings therein and enclosing a space, a rigid support secured to said casing, a vibratory member covering one of said openings and securely clamped between said support and said casing, said support being adapted to limit the amplitude of vibration of said vibratory member, a pair of whisker type contacts arranged at right angles to each other, inertia means secured to said support for pivotally mounting one of said pair of contacts, means including said vibratory member for vibrationally mounting the other of said pair of contacts, means settable at will for yieldably maintaining said pair of contacts in continuous engagement when the device is in a state of rest, and a normally expanded, gas-filled collapsible member over the other of said openings providing a chamber in communication with said space, said member being collapsible in response to water pressure when said device is immersed in the water to force the gas therein into said space, thereby to increase the pressure on the inner surface of said vibratory member for balancing the water pressure on the outer surface thereof.
2. A device of the character disclosed adapted to be immersed in a body of water and comprising a casing having an opening therein, a rigid support secured to said casing, a vibratory member covering said opening and securely clamped between said support and said casing, a pair of whisker type contacts disposed in mutually perpendicular relation, means on said support pivotally mounting one of said pair of contacts, means mounting the other of said contacts for movement with said vibratory member, means yieldably maintaining said pair of contacts in continuous engagement when the vibratory member is at rest and providing cyclic contact closure with the application of vibrational energy to the device, and means sealed in said casing for equalization of the internal pressure with increases of external pressures as the device is immersed in a body of water.
